12 Claims. (Cl. 260—683.5)

1

This invention relates to the catalytic isomerization of hydrocarbons, and is more particularly concerned with an improved process for isomerizing paraffinic hydrocarbons having five to seven carbon atoms.

As is well known to those familiar with the art, compounds are said to be isomeric when they are composed of the same chemical elements in the same proportion by weight, but have different properties. Such compounds are referred to as isomers, and the reaction conditions of temperature, time, etc., of processes that effect the transformation of one isomer into another, accordingly called isomerization processes, are broadly referred to as isomerizing or isomerization reaction conditions. Structural isomerism is one type of isomerism and connotes that which involves compounds having the same empirical formulas and identical molecular formulas, but which have different structural formulas, and, consequently, different properties. Structural isomerism is referred to as chain isomerism when the isomerism is due to different arrangements of the carbon atoms in the carbon chain. Butane and 2-methyl propane or isobutane are typical examples of chain isomerism.

The production of isoparaffinic, or branched-chain paraffinic hydrocarbons, from the corresponding normal or straight-chain paraffinic hydrocarbons, and of more highly branched-chain paraffinic hydrocarbons from branched-chain paraffinic hydrocarbons is highly desirable because of the generally higher anti-knock ratings of the branched-chain paraffinic hydrocarbons. The branched-chain paraffinic hydrocarbons, generally, are also more reactive than the corresponding normal hydrocarbons, and, therefore, they are widely utilized in alkylation processes for the formation of alkylates comprising highly-branched paraffinic hydrocarbons boiling within the gasoline boiling range. Furthermore, isoparaffinic hydrocarbons, like isobutane, may be dehydrogenated to the corresponding isobutenes and these may be polymerized and subsequently hydrogenated to produce saturated motor fuels of high octane ratings.

Originally, the fixed gases obtained around petroleum refineries constituted an adequate supply of isoparaffinic hydrocarbons suitable for alkylation and polymerization operations. How-

2

ever, the ever increasing demand for high quality aviation gasoline has necessitated the discovery of additional sources of isoparaffinic hydrocarbons. Isomerization processes, whereby normal or straight-chain paraffinic hydrocarbons, the sources of which are plentiful, are converted into isoparaffinic or branched-chain paraffinic hydrocarbons, constitute one of the most important sources of isoparaffinic hydrocarbons now available.

Accordingly, numerous processes have been proposed for effecting the transformation of normal paraffinic hydrocarbons into isoparaffinic hydrocarbons. Ordinarily, these processes comprise the use of substances that facilitate the isomerization conversion, consequently referred to in the art as isomerization catalysts. Some of these isomerization processes employ, in addition to an isomerization catalyst, substances that increase the isomerization catalytic activity of the catalyst, hence called promoters. More recently, it has been discovered that in addition to the promoter, it is advantageous to carry out the catalytic isomerization operation in the presence of added quantities of other substances.

Although most of the so-called "acid" type catalysts, such as aluminum chloride, boron trifluoride, sulfuric acid, ferric chloride, zinc chloride, phosphoric acid, and the like, have been reported to catalyze the isomerization of hydrocarbons, aluminum chloride and aluminum bromide are, so far as is known, by far the most effective isomerization catalysts. The use of water, hydrogen chloride, and hydrogen bromide as promoters for the aluminum halide catalysts is quite common. Others have proposed the use of small amounts of hydrogen halide in conjunction with alkyl halides, of chlorine, of carbon dioxide, of hydrogen halide, and water, of hydrated inorganic salts, of preformed solutions of an aluminum halide in hydrogen chloride which has been liquified under pressure, and of compounds of the type $R-SO_2OH$, wherein R is either the hydroxyl group or a halogen, as isomerization catalysts. In some instances, the use of inert carriers in conjunction with aluminum halides with or without hydrogen halide promoters has also been suggested.

In the isomerization of normal butane, unmodified aluminum halides with or without hy-

hydrogen halide promoters have been used as catalysts with some success. However, since aluminum halides are also somewhat strong cracking and alkylation catalysts, their use as catalysts in the isomerization of the higher homologues of normal butane causes undesirable additional reactions, including cracking which may be followed by alkylation, henceforth referred to, in the interest of brevity, as side reactions, resulting in substantial yields of butanes and of hydrocarbons having molecular weights higher than those of the charge stocks.

It is well known that aluminum halides react with hydrocarbons to produce complex masses spoken of in the art as "sludges." These "sludges" have been found to be considerably less active as cracking catalysts than the aluminum halides themselves; hence, it has been proposed to use "sludges" preformed by the treatment of naphthas with aluminum halides, by the treatment of cyclohexene with aluminum halides, by the treatment of alkyl aromatics with aluminum halides, or to use a preformed "double compound" of aluminum halide-alkyl aromatic-alkyl halide. However, the use of these "sludges," although reducing the undesirable side reactions, does not completely inhibit them.

Accordingly, in isomerization operations involving the use of aluminum halides, it has been suggested to use so-called cracking inhibitors. Hydrogen used per se or in conjunction with propane, and metallic aluminum have been proposed as cracking inhibitors.

The formation of aluminum halide catalysts in situ is a very recent development in the catalytic isomerization of normal butane and its higher homologues. In these processes, the catalyst is produced in situ by the reaction of metallic aluminum in the form of chips, foil, flakes, grindings, etc., with a halogen or a compound capable of chemically reacting as the equivalent of a free halogen under the isomerization reaction conditions. Examples of these compounds are hydrogen halides, alkyl halides, organic acid halides, and mixtures thereof. Metallic aluminum in comminuted form may be placed in the reaction zone to form a stationary bed or a series of stationary beds through which the charge stock flows, or small amounts of comminuted metallic aluminum may be added to the charge stock and thereby carried into the reaction zone. If desired, small amounts of substances such as hydrogen chloride, that expedite the formation of Friedel-Crafts catalysts, as well as small amounts of water, may be advantageously used, as is well known in the art. The halogen or halogen-containing compound may be introduced directly into the reaction zone in the case where the comminuted metallic aluminum is placed therein prior to the isomerization operation, or the halogen or halogen-containing compound may be added to the charge stock in the case where the comminuted metallic aluminum is added to the charge stock.

Nevertheless, the processes of the prior art have never been entirely successful in inhibiting the undesirable side reactions that occur in the isomerization of hydrocarbons having five to seven carbon atoms.

A copending application, Serial Number 554,184, filed September 15, 1944, is directed to the process for effecting the isomerization of paraffinic hydrocarbons having five to seven carbon atoms inclusive, which comprises contacting said hydrocarbons in a reaction zone under isomeriza-

tion reaction conditions, with a nascent aluminum halide isomerization catalyst formed in said reaction zone under said isomerization reaction conditions, in the presence of an organic aromatic compound. In accordance with the process set forth in this copending application, undesirable side reactions that occur in the isomerization of paraffinic hydrocarbons having five to seven carbon atoms are practically completely eliminated.

We have now discovered that these side reactions of cracking and alkylation likewise may be practically completely eliminated if the activity, as a cracking catalyst, of the aluminum halide catalyst in statu nascendi is inhibited by the incorporation in the charge of small amounts of certain types of organic heterocyclic compounds. Under such conditions, the aluminum halide catalyst may be said to have specific isomerizing activity.

We have found that in the isomerization of paraffinic hydrocarbons having five to seven carbon atoms inclusive, in the presence of aluminum halide isomerization catalysts, it is possible to inhibit substantially completely undesirable side reactions including cracking and/or alkylation, by carrying out the isomerization operation using nascent aluminum halide isomerization catalysts formed in situ and in the presence of added, relatively small amounts of certain types of organic heterocyclic compounds.

It is understood that free halogens, hydrogen halides, as well as various organic halogen compounds capable of reacting with metallic aluminum to produce aluminum halides, may be used. From the commercial standpoint, however, the use of hydrogen halides is unquestionably preferable.

Accordingly, it is an object of the present invention to provide an efficient isomerization process. Another object is to provide an efficient process for isomerizing paraffinic hydrocarbons having five to seven carbon atoms inclusive. A further object is to afford an improved process for isomerizing paraffinic hydrocarbons having five to seven carbon atoms in the presence of nascent aluminum halide isomerization catalysts formed in situ. A more specific object is to provide a process for isomerizing paraffinic hydrocarbons having five to seven carbon atoms inclusive in which undesirable secondary reactions are practically completely inhibited. A very important object is to provide a process capable of carrying out the above objects by using small amounts of certain types of organic heterocyclic compounds.

Other objects and advantages of the present invention will become apparent to those skilled in the art from the following description taken in conjunction with the following drawings, in which:

Figure 1 shows a series of curves representing graphically the relationship between the conversion per pass of normal pentane into isopentane and into butane and residue, in the presence of aluminum chloride in statu nascendi, and the concentration of thiophene in the charge;

Figure 2 shows two curves representing graphically the relationship between the conversion per pass of normal pentane into isopentane in the presence of aluminum chloride, preformed and in statu nascendi, and the concentration of aluminum chloride based on the pentane charged;

Figure 3 shows two curves representing graphically the relationship between the conversion per

pass of normal pentane into butane and residue, in the presence of aluminum chloride, preformed and in statu nascendi, and the concentration of aluminum chloride based on the pentane charged;

Figure 4 shows two curves representing graphically the relationship between the total conversion per pass of normal pentane into isopentane, butane and residue, in the presence of aluminum chloride, preformed and in statu nascendi, and the concentration of aluminum chloride based on the pentane charged; and

Figure 5 shows two curves representing graphically the relationship between the conversion of normal pentane into isopentane in the presence of aluminum chloride, preformed and in statu nascendi, and the concentration of thiophene in the charge.

Broadly stated, the present invention provides a process for effecting the isomerization of paraffinic hydrocarbons having five to seven carbon atoms inclusive, which comprises contacting said hydrocarbons in a reaction zone under isomerization reaction conditions, with a nascent aluminum halide isomerization catalyst formed in said reaction zone under said isomerization reaction conditions, in the presence of certain types of organic heterocyclic compounds.

It must be clearly understood that when we speak of effecting the isomerization of hydrocarbons, we have reference to the conversion of normal paraffinic hydrocarbons into their iso or branched-chain forms, as well as the conversion of isoparaffinic or branched-chain paraffinic hydrocarbons into more highly branched forms.

An important feature of our invention is that in the isomerization of pentanes and hexanes, all undesirable side reactions are substantially completely inhibited.

Another feature is that in the isomerization of heptanes, the undesirable side reactions are almost completely inhibited.

A further feature is that the aluminum halide isomerization catalysts are utilized in their highest state of catalytic activity, i. e., in the nascent state, while the undesirable side reactions in the isomerization of pentanes, hexanes, and heptanes are inhibited.

Generally speaking, the organic heterocyclic compounds which we have found to have an inhibiting effect upon undesirable side reactions, during the isomerization of hydrocarbons, such as pentane, hexane, and heptane, in the presence of aluminum halide isomerization catalysts in statu nascendi, comprise compounds containing an heterocyclic five-membered ring and compounds containing an heterocyclic six-membered ring. Thiophene, furan, furfuraldehyde, α -picoline, pyridine, piperidine, carbazole, pyridine hydrochloride, indole, and quinoline may be mentioned specifically by way of non-limiting examples of organic heterocyclic compounds suitable for the process of the present invention.

It must be noted that these heterocyclic compounds may be used per se or in admixture with diluents not undesirable, provided that the concentration of the heterocyclic compounds is sufficiently high so that the diluents do not materially affect the reaction, when a sufficient amount of material is used to achieve the effective heterocyclic compound concentrations.

Referring now more particularly to the curves shown in Figure 1, which are based on data obtained by treating normal pentane at a temperature of about 100° C. for about 1 hour, using

charge stocks containing in addition to 100 parts of normal pentane, 16.1 parts by weight of aluminum, 6.9 parts by weight of dry, gaseous hydrogen chloride, and varying amounts of thiophene, it will be observed that in the absence of thiophene, the catalyst causes side reactions of cracking and alkylation as readily as isomerization, so that large amounts of butanes and heavy residue are formed. Upon the addition of thiophene, the undesirable side reactions are inhibited, until at a concentration of about 0.5% by weight of thiophene, the undesirable side reactions are for all practical purposes, completely suppressed, so that the isomerization reaction proceeds unhindered, thereby producing high yields of isopentane. When the concentration of thiophene exceeds about 2.5% by weight of the pentane charged, the catalyst is deactivated not only with respect to the side reactions, but also with respect to the isomerization reaction, so that substantially unreacted normal pentane is recovered. It must be noted, however, that appreciable deactivation of the catalyst, with respect to isomerization, takes place when the concentration of thiophene is of the order of about 1.0% by weight. From the curves of Figure 1, it would appear that for a hydrogen chloride concentration of 6.9 parts by weight, the most practical thiophene concentrations to be used, to insure substantially complete suppression of undesirable side reactions and concurrent maximum yields of isopentane per pass, lie in the comparatively narrow range of about 0.5% to about 2.0%.

The range of concentrations necessary to insure substantially complete suppression of undesirable side reactions and concurrent maximum yields of isomer per pass of our heterocyclic compound inhibitors varies with each compound. Too large a concentration of any of the heterocyclic compound inhibitors of our invention will inhibit substantially all reaction. In any particular case, the most desirable concentration of the heterocyclic compound inhibitor to be used can be readily ascertained by one skilled in the art, the essential desiderata, in accordance with the present invention as illustrated by the curves shown in Figure 1, being a substantially complete suppression of undesirable side reactions with concurrent high ultimate yields of isomer.

When no inhibitors are employed, we have found that under comparable conditions, there is substantially little difference between operations wherein aluminum halide catalysts in statu nascendi are used, and operations wherein preformed aluminum halide catalysts are employed, in so far as the yields of isomers and the amounts of undesirable products produced are concerned. As illustrated by the curves shown in Figures 2, 3 and 4, which are based on data obtained by treating normal pentane at a temperature of about 100° C. for about 1 hour, in the presence of varying amounts of preformed aluminum chloride and of aluminum chloride formed in situ, the production of cracked products, of higher boiling hydrocarbons, and of isomerized hydrocarbons is essentially the same irrespective of the catalyst employed. The use of aluminum halides in statu nascendi may be considered, therefore, a convenient method of introducing the catalyst in the reaction zone. No essential advantage may be claimed for it over the use of preformed aluminum halides, with respect to the results obtained. In each case, curve A is based upon the use of metallic aluminum and hydrogen chloride, while curve B is based upon the use of an amount of

aluminum chloride approximately equal to that formed in the corresponding run on curve A. The aluminum chloride was activated with hydrogen chloride in amounts that were in excess of that remaining after the formation of aluminum chloride in situ in the corresponding run on curve A.

As has been pointed out by several investigators, the advantage of using small amounts of hydrogen halides (on the order of 1% to 2%) in conjunction with aluminum halides is merely a prolongation of the catalytic activity of the aluminum halide catalysts. Accordingly, the curves shown in Figures 2, 3 and 4, may be considered as evidence that, in so far as isomerization reactions are concerned, aluminum chloride, formed in situ from metallic aluminum and hydrogen chloride, is essentially no better or no worse than an equivalent amount of preformed aluminum chloride.

Referring now more particularly to the curves shown in Figure 5, which are based on data obtained by treating normal pentane at a temperature of about 100° C. for about 1 hour, using charge stocks containing in addition to 100 parts by weight of normal pentane, 16.1 parts by weight of metallic aluminum, 6.9 parts by weight of hydrogen chloride, and varying amounts of thiophene, and amounts of aluminum chloride, hydrogen chloride, and thiophene substantially equal to those in the corresponding runs where metallic aluminum and hydrogen chloride were employed, respectively; it will be observed that under substantially identical isomerizing conditions, the combination of metallic aluminum, hydrogen chloride and thiophene is far more effective than the combination of aluminum chloride and thiophene even though an amount of preformed aluminum chloride equal to that formed in situ in the first instance, and an amount of hydrogen chloride substantially equal to that remaining after formation of the aluminum chloride in situ, and present as promoter in the first instance, were used. It is apparent, therefore, that our heterocyclic compound inhibitors partially inhibit the isomerization catalytic activity of aluminum chloride while substantially completely inhibiting its cracking and/or alkylation catalytic activity. Our inhibitors suppress the isomerization catalytic activity of aluminum chloride in situ nascendi to a far smaller degree than they inhibit the isomerization catalytic activity of preformed aluminum chloride, while still substantially completely inhibiting its cracking and/or alkylation catalytic activity. Hence, although as illustrated by the curves shown in Figures 2, 3 and 4, there is no particular advantage in the use of metallic aluminum and hydrogen halides in place of preformed aluminum halides, other than one of convenience, there are decided advantages in accordance with the present invention in the use of metallic aluminum, hydrogen halides, and our heterocyclic compound inhibitors.

We have not been able to find any evidence that in the process of the present invention, other metals, such as iron or zinc, can be used instead of aluminum. Since the isomerization catalytic activity of the halides of such metals is considerably less than that of aluminum halides, it is probable that in our type of operation the halides of these metals are formed in amounts insufficient to promote reaction.

The present process is capable of converting normal paraffinic hydrocarbons into their corresponding branched-chain or iso forms, as well as

branched-chain paraffinic or isoparaffinic hydrocarbons into more highly branched forms. The charge stocks may comprise mixtures of two or more normal or branched-chain paraffinic hydrocarbons which may contain also small amounts of normal and/or branched-chain olefinic hydrocarbons. It should be pointed out, however, that the presence of unsaturates, even in small amounts, deactivates aluminum halide catalysts, and therefore increases considerably catalyst consumption. Generally speaking, any hydrocarbon mixture comprising normal or branched-chain paraffinic hydrocarbons in predominant amounts, is a suitable charge stock for the process of our invention. We have found, however, that the effectiveness of our heterocyclic compound inhibitors decreases with increasing molecular weight of the hydrocarbons to be isomerized. No inhibitor appears to be necessary in the isomerization of normal butane. Our inhibitors substantially completely suppress cracking and other undesirable side reactions in the isomerization of normal pentane and normal hexane, almost completely suppress undesirable side reactions in the isomerization of normal heptane, and are of little value in the isomerization of normal octane.

The isomerizing conditions of the process of the present invention include wide ranges of temperatures, time of contact, catalyst concentration, pressures, etc., as is well known in the art. It must be clearly understood, however, that all these factors are more or less inter-related, and that under a given set of conditions, the ease of formation of aluminum halide from metallic aluminum and the halogen-containing substance, will govern to a considerable extent, the temperature and time of reaction. Ordinarily, temperatures varying between about 75° C. and about 200° C., and a contact time varying between about several seconds and about one hour, depending upon the temperature, the pressure and the amounts of hydrogen halide, aluminum, and heterocyclic inhibitor, produce good results.

The isomerization reaction may be carried out in either the liquid phase or in the gaseous phase, depending upon the particular conditions used. We prefer to use a liquid phase operation, the pressure employed being sufficient to maintain the hydrocarbons as well as the inhibitor, in the liquid phase at a temperature within the range indicated hereinbefore.

The process may be carried out as a batch, continuous or semi-continuous type of operation. Particularly when the process is conducted on a commercial scale, economic considerations make it advantageous to operate in a continuous manner. For efficient operation, whether the process is carried out on a batch or continuous basis, it is essential that the reactants be intimately contacted with one another. This may be achieved in several ways and in apparatuses that are well known in the art.

In accordance with our invention, we obtain a product containing substantial amounts of branched-chain hydrocarbons which may be separated from the effluent and fractionated to recover the desired isomer or isomers. The unconverted constituents may then be recycled with fresh charge stock, to the isomerization reaction zone for further treatment. Small amounts of aluminum halide "sludge," of the order of 1-5% by weight of hydrocarbon charge, are formed in the process. This sludge represents the main source of process loss. If relatively high proportions of hydrogen halide are used and the sludge

is formed in a comparatively large amount, the sludge may be still active. In continuous operation, these active sludges may be recycled to the reactors for better utilization of the catalyst.

The following detailed examples are for the purpose of illustrating modes of carrying out the process of our invention, it being clearly understood that the invention is not to be considered as limited to the specific manipulation and conditions set forth in the examples. As it will be apparent to those skilled in the art, a wide variety of other heterocyclic compounds within the scope of our invention may be used as inhibitors.

Example 1

A mixture containing 94.7 parts by weight of normal pentane, 5.3 parts by weight of cyclopentane, 0.86 part by weight of pure thiophene, and 16.1 parts by weight of aluminum turnings, was charged into a stirring autoclave. 6.9 parts by weight of dry, gaseous hydrogen chloride were added and then the autoclave was heated to a temperature of 100° C. and maintained at about this temperature for one hour. The autoclave was then cooled for about ten minutes in ice-water and any residual gas was released slowly through a soda-lime tube which scrubbed out any remaining hydrogen chloride. This gas was subsequently passed through a trap maintained at low temperatures with a dry ice-acetone cooling mixture. Only traces of a liquid, identified as pentanes, were carried out by the hydrogen chloride. The synthetic crude remaining in the autoclave was water-washed, and then alkali-washed until all acid had been removed from the hydrocarbon mixture. Finally, the synthetic crude was dried over calcium chloride and analyzed by Podbielnik distillation with the following results:

	Per cent by weight
Isopentane	29.9
Normal pentane	63.3
Residue	6.8

In the absence of thiophene, the synthetic crude would analyze as follows:

	Per cent by weight
Isopentane	32.3
Normal pentane	19.3
Butanes	26.7
Residue	21.7

Example 2

The run described in Example 1 was repeated but in this case, the 0.86 part by weight of thiophene was replaced by 1.69 parts by weight of pyridine hydrochloride. The synthetic crude analyzed as follows:

	Per cent by weight
Isopentane	23.3
Normal pentane	69.7
Residue	7.0

Example 3

The run described in Example 1 was repeated but in this case, the 0.86 part by weight of thiophene was replaced by 1.1 parts by weight of piperidine. The synthetic crude analyzed as follows:

	Per cent by weight
Isopentane	14.4
Isobutane	1.2
Normal pentane	77.8
Residue	6.6

Example 4

The run described in Example 1 was repeated but in this case, the 0.86 part by weight of thiophene was replaced by 2.74 parts by weight of quinoline and the charge contained 99.4 parts by weight of normal pentane and 0.6 part by weight of cyclopentane. The synthetic crude analyzed as follows:

	Per cent by weight
Isopentane	6.8
Isobutane	1.1
Normal pentane	86.8
Residue	5.3

Example 5

The run described in Example 1 was repeated but in this case, the 0.86 part by weight of thiophene was replaced by 2.15 parts by weight of α -picoline and the charge contained 100 parts by weight of normal pentane. The synthetic crude analyzed as follows:

	Per cent by weight
Isopentane	15.3
Butanes	5.4
Normal pentane	75.3
Residue	4.0

Example 6

The run described in Example 1 was repeated but in this case, the charge was 100 parts by weight of normal hexane, 0.82 part by weight of pure thiophene, 15.4 parts by weight of aluminum turnings, and 9.5 parts by weight of dry, gaseous hydrogen chloride. The synthetic crude analyzed as follows:

	Per cent by weight
Butanes and pentanes	Trace
2,2-dimethyl butane	5±3
2,3-dimethyl butane	5±3
2-methyl pentane	8±3
3-methyl pentane	10±3
Normal hexane	70±10
Residue	1.8

In the absence of thiophene, the synthetic crude would analyze as follows:

	Per cent by weight
Butanes and pentanes	47
2,2-dimethyl butane	4
2,3-dimethyl butane	4
2-methyl pentane	6
3-methyl pentane	2
Normal hexane	23
Residue	14

Example 7

The run described in Example 1 was repeated but in this case, the charge was 100 parts by weight of pure normal heptane, 14.5 parts by weight of aluminum turnings, 9.4 parts by weight of dry, gaseous hydrogen chloride, and 7.94 parts by weight of pyridine hydrochloride. The reaction mixture was maintained at about 100° C. for about 2 hours. The synthetic crude analyzed as follows:

	Per cent by weight
Butanes and pentanes	14
2,3-dimethylpentane	Trace
2-methylhexane	3±2
3-methylhexane	5±2
Normal heptane	76±5
Residue	2

11

In the absence of pyridine hydrochloride, the synthetic crude would analyze as follows:

	Per cent by weight
Butanes and pentanes	30
2,3-dimethylpentane	1±1
2-methylhexane	4±2
3-methylhexane	5±3
Normal heptane	34±3
Residue	26

Although the present invention has been described in conjunction with preferred embodiments, it is to be understood that modifications and variations may be resorted to without departing from the spirit and scope of the invention, as those skilled in the art will readily understand. Such variations and modifications are considered to be within the purview and scope of the appended claims.

We claim:

1. In the process which involves subjecting a heptane to an isomerization reaction, which includes contacting said heptane in a reaction zone under isomerization reaction conditions, with nascent aluminum chloride isomerization catalyst formed in said reaction zone under said isomerization reaction conditions; the improvement which comprises effecting said isomerization reaction in the presence of thiophene, in amounts permitting the isomerization reaction and sufficient to materially suppress side reactions.

2. The process for effecting the isomerization of a hexane, which comprises contacting said hexane in a reaction zone under isomerization reaction conditions, with nascent aluminum chloride isomerization catalyst formed in said reaction zone under said isomerization reaction conditions, in the presence of thiophene, in amounts permitting the isomerization reaction and sufficient to substantially completely inhibit side reactions.

3. The process for effecting the isomerization of a pentane, which comprises contacting said pentane in a reaction zone under isomerization reaction conditions, with nascent aluminum chloride isomerization catalyst formed in said reaction zone under said isomerization reaction conditions, in the presence of thiophene, in amounts permitting the isomerization reaction and sufficient to substantially completely inhibit side reactions.

4. The process for effecting the isomerization of a paraffinic hydrocarbon having five to seven carbon atoms inclusive, which comprises contacting said hydrocarbon in a reaction zone under isomerization reaction conditions, with a nascent aluminum halide isomerization catalyst formed in said reaction zone under said isomerization reaction conditions, in the presence of thiophene, in amounts permitting the isomerization reaction and sufficient to materially suppress side reactions.

5. The process for effecting the isomerization of a heptane, which comprises contacting said heptane in a reaction zone under isomerization reaction conditions, with nascent aluminum chloride isomerization catalyst formed in said reaction zone under said isomerization reaction conditions, in the presence of material selected from the group consisting of thiophene, furfuraldehyde, furan, pyridine, piperidine, α -picoline, carbazole, indole, and quinoline, in amounts permitting the isomerization reaction and sufficient to materially suppress side reactions.

6. The process for effecting the isomerization

12

of a hexane, which comprises contacting said hexane in a reaction zone under isomerization reaction conditions, with nascent aluminum chloride isomerization catalyst formed in said reaction zone under said isomerization reaction conditions, in the presence of material selected from the group consisting of thiophene, furfuraldehyde, furan, pyridine, piperidine, α -picoline, carbazole, indole, and quinoline, in amounts permitting the isomerization reaction and sufficient to substantially completely inhibit side reactions.

7. In the process which involves subjecting a pentane to an isomerization reaction, which includes contacting said pentane in a reaction zone under isomerization reaction conditions, with nascent aluminum chloride isomerization catalyst formed in said reaction zone under said isomerization reaction conditions; the improvement which comprises effecting said isomerization reaction in the presence of material selected from the group consisting of thiophene, furfuraldehyde, furan, pyridine, piperidine, α -picoline, carbazole, indole, and quinoline, in amounts permitting the isomerization reaction and sufficient to substantially completely inhibit side reactions.

8. In the process which involves subjecting a paraffinic hydrocarbon having five to seven carbon atoms inclusive, to an isomerization reaction, which includes contacting said hydrocarbon in a reaction zone under isomerization reaction conditions, with a nascent aluminum halide isomerization catalyst formed in said reaction zone under said isomerization reaction conditions; the improvement which comprises effecting said isomerization reaction in the presence of material selected from the group consisting of thiophene, furfuraldehyde, furan, pyridine, piperidine, α -picoline, carbazole, indole, and quinoline, in amounts permitting the isomerization reaction and sufficient to substantially completely inhibit side reactions.

9. The process for effecting the isomerization of a heptane, which comprises contacting said heptane in a reaction zone under isomerization reaction conditions, with nascent aluminum chloride isomerization catalyst formed in said reaction zone under said isomerization reaction conditions, in the presence of pyridine, in amounts permitting the isomerization reaction and sufficient to materially suppress side reactions.

10. In the process which involves subjecting a hexane to an isomerization reaction, which includes contacting said hexane in a reaction zone under isomerization reaction conditions, with nascent aluminum chloride isomerization catalyst formed in said reaction zone under said isomerization reaction conditions; the improvement which comprises effecting said isomerization reaction in the presence of pyridine, in amounts permitting the isomerization reaction and sufficient to substantially completely inhibit side reactions.

11. The process for effecting the isomerization of a pentane, which comprises contacting said pentane in a reaction zone under isomerization reaction conditions, with nascent aluminum chloride isomerization catalyst formed in said reaction zone under said isomerization reaction conditions, in the presence of pyridine, in amounts permitting the isomerization reaction and sufficient to substantially completely inhibit side reactions.

12. The process for effecting the isomerization

of a paraffinic hydrocarbon having five to seven carbon atoms inclusive, which comprises contacting said hydrocarbon in a reaction zone under isomerization reaction conditions, with a nascent aluminum halide isomerization catalyst formed in said reaction zone under said isomerization reaction conditions, in the presence of pyridine, in amounts permitting the isomerization reaction and sufficient to materially suppress side reactions.
